UNITED STATES PATENT OFFICE

113,874

DESIGN FOR A POT COVER CABINET

Robert J. Miller, Chicago, Ill.

Application November 9, 1938, Serial No. 80,982

Term of patent 7 years

To all whom it may concern:

Be it known that I, Robert J. Miller, of the United States, residing at Chicago, in the county of Cook and State of Illinois, have invented a new, original, and ornamental Design for Pot Cover Cabinets, of which the following is a specification, reference being had to the accompanying drawing, forming part thereof in which the figure is a perspective view of a pot cover cabinet showing my new design.

I claim:

The ornamental design for a pot cover cabinet, as shown.

ROBERT J. MILLER.
